UNITED STATES PATENT OFFICE.

ALEXANDER McNAB, OF BRIDGEPORT, CONNECTICUT, ASSIGNOR TO THE McNAB COMPANY, OF BRIDGEPORT, CONNECTICUT, A CORPORATION OF CONNECTICUT.

BOILER-CIRCULATOR.

1,155,832.

Specification of Letters Patent.

Patented Oct. 5, 1915.

Application filed November 19, 1914. Serial No. 872,938.

To all whom it may concern:

Be it known that I, ALEXANDER McNAB, a subject of the King of England, residing at the city of Bridgeport, county of Fairfield, State of Connecticut, United States of America, have invented certain new and useful Improvements in Boiler-Circulators; and I do declare the following to be a full, clear, and exact description of the invention, such as will enable others skilled in the art to which it appertains to make and use the same.

This invention relates to certain new and useful improvements in automatic circulator for steam boiler, and the primary object thereof is to provide a circulator in which all of the parts thereof are rigidly connected so as to present a practically integral unit enabling the circulators to be produced with economy in material and workmanship, and to be both strong and serviceable.

Further, the invention aims to provide a circulator which can be easily and quickly installed in a boiler with the use of but a single tool, namely, a wrench, and to also provide a circulator in which same has a multiplicity of spaced bearing points on the fire tubes so as to be more effectively and firmly secured to the latter.

Still further, the invention aims to provide a circulator which has novel nozzle means incorporated therein to assist in rapid flow and deflection of the water.

Other and further objects will be later set forth in the course of the following description.

In the drawings: Figure 1 is a section on the line 1—1 of Fig. 2; Fig. 2 is a section on the line 2—2 of Fig. 1; Fig. 3 is an enlarged detail view showing the vanes and the deflector nozzles at the top of the fire tubes; Fig. 4 is a similar view of the vanes at the bottoms of the fire tubes; and Fig. 5 is a top plan view of Fig. 4.

In proceeding in accordance with the present invention, pairs of upper and lower side plates 1 are employed, which extend longitudinally of the boiler and are secured to the fire tubes by the provision of angle brackets 2 which are bolted or riveted to the plates 1 and have perforations formed in their horizontal parts, through which perforations, hook bolts 3 pass, the hooks 4 of which bolts engage the fire tubes T, while nuts 5 are threaded on the bolts 3 and im-

pinge against the lugs 2, so as to draw the hooks 4 tightly into engagement with the tubes T.

The side plates 1 are connected by the blades or vanes 6, which blades or vanes have their ends turned at right angles at 7 and riveted to the respective side plates 1 so that the blades are stationarily or rigidly affixed to the side plates 1.

It will be noted that in the present embodiment of the invention there are six blades or vanes 6 at the tops and at the bottoms of the banks of fire tubes, the blades at the lower ends of the tubes inclining rearwardly of the boiler while the blades at the tops of the tubes incline toward the front of the boiler, which opposite inclination of the blades is for the purpose of causing the water to travel in the path indicated by the arrows in Fig. 2.

The alternate blades at the tops of the tubes are provided with forwardly projecting horizontal portions 8, the spaces 9 between adjacent portions 8 constituting nozzles, the nozzles being arranged in superposed order for the purpose of directing the boiling water toward the front of the boiler.

As shown in Figs. 2 and 3 the nozzles 9 provide independent passages for the water, or in other words the nozzles perform the function of dividing the boiling water into upper and lower strata to assist in increasing the rapidity of the flow of the water. The nozzles are arranged so that the one next to the fire tubes is nearest the boiler front, or in other words the nozzles are arranged in step-like order.

It will also be noted from the drawings that the longitudinal side edges of the blades adjacent to the tubes T contact with the latter so that by tightening the nuts on the bolts 3 the blades may be easily and quickly applied to or removed from the tubes, and since the blades rigidly connect the side plates 1 it will be apparent that a unitary and rigid structure is provided which can be easily moved back and forth on the tubes for the purpose of cleaning the latter.

Referring to Figs. 1 and 2 of the drawings it will be seen that a transverse deflecting element here shown as formed in two sections 9^a is secured to the back 10 of the boiler casing by rivets 11 and has a horizontal forwardly projecting portion 12 secured by means of hook bolts 13 to the boiler

braces 14. This element extends entirely across the boiler and serves to assist in deflecting the water toward the boiler front.

It will be observed that in the present case, since each of the blades 6 has a longitudinal edge engaging the tubes, that a most firm and substantial foundation or anchorage for the structure is provided. The blades in proximity to the combustion chamber are arranged in closer relation to each other than are the blades more remotely situated with respect to the combustion chamber.

The operation briefly summarized is as follows: As the water is heated it rapidly rises upwardly and impinges against the lower set of blades and is deflected by the latter toward the rear of the boiler, the water continuing to rise until it engages the upper set of blades and is deflected by the latter toward the front of the boiler, whereupon the water will descend and again pursue the course of travel aforementioned. The close relation of the blades as the combustion chamber is approached results from the fact that the heat is more intense adjacent said chamber and therefore the upward current of the water is proportionately accelerated and requires deflection accordingly. At the front of the boiler where the heat is of less degree, the water is comparatively sluggish and is readily influenced by the rapidly moving hot currents, which therefore allows the blades to be more widely spaced.

What is claimed is:

1. In a boiler circulator, a pair of spaced

side plates, and blades rigidly connected at their ends to the side plates and formed at their upper portions into horizontally extending nozzles.

2. In a boiler circulator, a series of spaced blades adapted to be transversely arranged with respect to the boiler tubes, some of said blades having their upper portions formed into horizontally extending gradient nozzles.

3. In a boiler circulator, a series of spaced blades adapted to be transversely arranged with respect to the boiler tubes, some of said blades being formed into nozzle portions which latter extend in horizontal successively overlapping relation to form superposed water passages.

4. In a boiler circulator, a series of blades, and a forward horizontal extension on alternate blades, said extensions forming superposed nozzles.

5. In a boiler circulator, blades forming passages and horizontally extending nozzles overlying the passages and communicating therewith.

6. In a boiler circulator, spaced side plates, and a series of transverse inclined blades rigidly connected at their ends to said plates, the distance between said blades gradually increasing as they approach the outer wall of the boiler.

In testimony whereof I affix my signature in presence of two witnesses.

ALEXANDER McNAB.
